CHARLES P. TOLMAN, OF KEW GARDENS, NEW YORK.

METHOD OF AND APPARATUS FOR TREATING HYDROCARBONS.

Application filed August 26, 1926. Serial No. 131,572.

My present invention relates to the treating of hydrocarbons by heat with the view either of simply distilling same or and more particularly, of obtaining therefrom, by cracking, hydrocarbons having a lower molecular weight than the starting material.

In the heat treatment of oil or other hydrocarbon, it is very important not to overheat portions thereof, as by so doing excessive amounts of carbon and gas are formed which not only represent a waste of the hydrocarbon, but particularly in case of the carbon, present a serious problem in their removal from the system. For this reason and others it has been proposed to heat hydrocarbon oil by commingling therewith a heating fluid whose temperature can be accurately controlled in contradistinction to heating by means of fireheated stills and the like which commonly produce local overheating. The mode of heating mentioned has the further advantage that the heating fluid can be mixed intimately with the oil, and hence impart to it a uniform degree of temperature. After long study of the problem I have been led to choose mercury or an equivalent substance, as a highly desirable vehicle for imparting the heat necessary for the cracking or other heat treatment of the oil or other hydrocarbon. The reasons for the selection of mercury for this purpose are chiefly as follows:

1. Its vaporizing characteristics are such that the comparatively high temperature necessary for cracking can be obtained without excessive pressure, and its vapor can be superheated and the relation between temperature and pressure thereby divorced.
2. It is easily condensed, and in contrast to steam, for example, it thus greatly relieves the condensers.
3. It is easily separated from the oil and is returnable to the boiler by gravity.
4. It carries nothing in solution.
5. It exerts a desirable catalytic effect upon the oil undergoing treatment.

In thus employing mercury for imparting heat to the oil by physically contacting it therewith, a further problem is presented by the fact of the difference in the vapor-pressure characteristics of the mercury vapor and oil. For example, in order to produce a temperature of the mercury vapor of, say, 800° F., it would ordinarily be necessary to employ a pressure of mercury of approximately 45 lbs. per square inch since mercury boils at this temperature and pressure. To obtain a temperature of 900° F., it would be necessary to use saturated mercury vapor having a boiler pressure of 90 lbs. per square inch, etc. On the other hand, the vapor tension of hydrocarbon oils is relatively much greater than that of mercury so that a temperature of 800° F., for example, would produce saturated oil vapor of a much higher pressure than that corresponding to the mercury vapor, or 45 lbs. per square inch. Therefore since ordinarily it is the rule to employ cracking temperatures of 800° and above, a fairly high pressure, both of mercury and oil would be contemplated by a simple mixing of the mercury vapor and liquid oil. However, it has been demonstrated by Leslie and Potthoff, see Jour. Am. Chem. Soc., volume 18, page 776, and substantiated by applicant's own observation that pressure has relatively little effect upon cracking, and hence the very high pressures which have been usual practice in the art are unnecessary. Accordingly, a feature of my present invention resides in employing mercury vapor which is superheated prior to its contact with the oil and which is furthermore under comparatively low pressures whereby the necessary temperature for cracking may be had without the employment of pressures which have been shown to be excessive. It is thus possible to introduce the heated mercury vapor directly into liquid oil (or solid hydrocarbons), since by the use of superheat the temperature of the mercury may be made equal to that of the vaporized saturated hydrocarbon vapors. However, I find it preferable first to evaporate the hydrocarbons in an evaporator of common type, but without effecting substantial cracking of such vapors, and then introduce them, together with the superheated mercury vapor into a suitable reaction chamber wherein the cracking is to take place. This permits low pressures to be employed and also has the further advantage that a portion of the total

heat necessary for accomplishing the conversion of the oils to be furnished by ordinary means, as by directly fired means, or by waste heat apparatus, and thus saves the mercury vapor for the upper and very much more important part of the heating cycle. On the other hand, care is taken that the vaporizing of the oil is accomplished with substantially no local overheating or cracking, a condition which is easily attained due to the comparatively low temperature involved. Thus, by the arrangement described, the discrepancy of the temperature-vapor pressure is taken care of while permitting the use of low pressures.

After the vaporized (or solid) hydrocarbon has been subjected to the action of the hot mercury vapor, the resulting vapors are led off, and condensed, and the mercury separated and returned to the boiler. The hydrocarbon products are then fractionally condensed or disposed of in known ways for the obtainment therefrom of their contained gasoline or other desired product.

My invention will be better understood by reference to the following detailed description taken with the accompanying drawing forming a part of this specification, which shows more or less diagrammatically a system of apparatus for carrying out my invention.

Referring now to the drawing by characters of reference: 10 denotes a mercury boiler of known type having a mercury vapor offtake 11 communicating with the heating coil or other heating surface of superheater 12, the heat of which may be suitably varied. Here the desired amount of superheating is imparted to the vapors. From superheater 12 the mercury vapor is led through pipe 13 into the reaction chamber 14. Communicating with the reaction chamber is also the evaporator 17 into which the oil undergoing treatment is introduced through a pipe 18. A pipe 19 for either steam or a neutral gas to assist the vaporization also communicates with the evaporating space of the evaporator or boiler 17. A pipe 20 having a valve 32 admits vapor from the evaporator 17 to the reaction chamber 14. To take care of the residue from evaporator 17 a residue tank 22 is provided. Non-return valves, 13^a and 20^a are preferably provided in pipes 13 and 20 respectively.

The products of reaction from the chamber 14 are led therefrom through a pipe 24, thence to condenser 25 and thence to a separator 26 wherein the separation of the liquid mercury from the liquefied hydrocarbons is effected. The liquid hydrocarbon products are removed from the separator 26 by means of a pipe 28 communicating with a receiver 29. Uncondensed vapors and gases are also conducted from the separator 26 by means of a pipe 30. The final product

of the system shown is led off through pipe 31. Mercury is returned to the boiler from separator 26 through a pipe 33' having therein a suitable pump 34', in case such should be necessary. The mercury may be introduced into the system by any suitable means as through the extension 33^a of pipe 33' beyond the separator 26.

My invention contemplates not only the cracking of liquid hydrocarbons, including coal tar or liquids derived from the coke industry, but also the distillation and cracking of solid substances yielding hydrocarbons as for example: shale, oil-bearing sands, materials of bituminous nature such as, soft coal, lignite, etc.

It will be noted that by virtue of my improved system of treating hydrocarbons, the temperature may be maintained at any suitable value depending upon the nature of the material undergoing treatment. This temperature for the mercury will ordinarily run over 700° F., and under 1100° F. As previously mentioned, my improved system is particularly adapted to the use of comparatively low pressures e. g. 50 lbs. and under, although I do not limit myself to any particular pressure range. Furthermore, and as has been previously mentioned, the heat necessary for bringing about the cracking reaction is furnished substantially entirely by the mercury vapor, this having the effect of eliminating entirely all danger of local overheating with the attendant production of carbon and gas.

It will be understood that the foregoing apparatus is illustrative only and accordingly, I have not shown various auxiliary apparatus such as: valves, gages, pipes for venting and draining, etc., which while necessary for the most efficient operation of the system are not required for the comprehension of the invention and furthermore form, per se no part thereof. It will furthermore be understood that various apparatus for fractionally condensing the reaction products and heating the entering oil thereby may be employed if desired.

Having now described my invention and the principle thereof:

What I claim is:

1. In the method of cracking hydrocarbon compounds the steps which consist in vaporizing mercury, superheating the produced vapor to above the desired cracking temperature, subjecting the hydrocarbon to vaporizing conditions, but without causing substantial cracking thereof and commingling the hydrocarbon vapor produced with said superheated mercury vapor, said mercury vapor being of such thermal quality as to temperature and heat units as to constitute substantially the sole source of heat for said cracking reaction.

2. In the method of cracking hydrocar-

bon compounds, the steps which consist in vaporizing mercury, superheating the produced vapor to above the desired cracking temperature, subjecting the hydrocarbon material to vaporizing conditions but without causing substantial cracking thereof and commingling the hydrocarbon vapor pro-

duced with said superheated mercury vapor and maintaining a superatmospheric total pressure of the reacting components below 10 50 pounds per square inch.

In testimony whereof I have affixed my signature to this specification.

CHARLES P. TOLMAN.
